UNITED STATES PATENT OFFICE.

HARRY A. YEIDER, OF GRAND RAPIDS, MICHIGAN, ASSIGNOR TO MICHIGAN HEARSE AND MOTOR COMPANY, A CORPORATION OF MICHIGAN.

FLOWER-SUPPORTING DEVICE FOR HEARSE.

1,251,163.

Specification of Letters Patent. Patented Dec. 25, 1917.

Application filed November 17, 1916. Serial No. 131,860.

To all whom it may concern:

Be it known that I, HARRY A. YEIDER, a citizen of the United States, residing at Grand Rapids, in the county of Kent and 5 State of Michigan, have invented new and useful Improvements in Flower-Supporting Devices for Hearses, of which the following is a specification.

The present invention relates to flower 10 supporting devices for hearses; and its object is generally to provide an improved device of this character whereby flowers and the like accompanying the casket may be readily and without injury placed in and 15 removed from the hearse; and more particularly, to provide a belt movably carried on spaced members, as rotatable rolls, on which belt the flowers, etc., may be placed.

This, and any other objects appearing 20 hereinafter, are attained by and the invention finds preferable embodiment in, the structure hereinafter described and illustrated by the accompanying drawings, in which:—

25 Figure 1 is a side view of a hearse in which my device is mounted, the near side wall of the hearse being broken away to show such device;

Fig. 2 is a sectional view of the same taken 30 on a vertical plane corresponding to line A—A of Fig. 1; and,

Fig. 3 is a view in perspective of said device.

In the embodiment of the invention chosen 35 for illustration by the drawings and for detailed description in the body of this specification, the side walls, 1, 2 of the hearse 3 carry inside the hearse my device which comprises the horizontally disposed members 4, 5 above the space provided for the casket, and spaced apart, one near the front 40 part of the hearse's interior and the other near the rear part thereof and adjacent the end door 6. Preferably these members are 45 rotatable rolls, as shown, and are journaled on parallelly disposed bars 7, 8, the roll near the door being provided with a hand-operable wheel 9 whereby the roll may be rotated as desired. These bars are preferably slid- 50 ably movable in ways 10, 11, one way being carried by one side wall of the hearse, and the other by the other side wall thereof, so that the entire frame 12 of which these bars form a part, may be slid out and re- 55 moved from the hearse when desired. This

frame is, as shown, provided with rods 13 extending parallelly with the longitudinal direction of said bars, and around which rods in their endwise direction passes the broad belt 14 adapted to support flowers and 60 the like, and carried by said rolls. It will be seen that such rods serve to support the upper portion of the belt, and by reason of their extending in said direction, facilitate the ready sliding movement of the upper 65 part of the belt with its load of flowers, etc., resting on said rods.

In order to tighten the belt, the journal bearings 15 of the roll 5 may be moved relatively to the other roll by the screws 16. 70

It will be seen that flowers and the like may be placed on the belt near the door, whereupon the belt being turned they may be carried toward the front of the hearse; then more flowers may be placed on a vacant 75 portion of the belt and moved in like manner; and that the flowers may be moved toward the door by turning the belt oppositely to remove them; and that in such movements they will be kept against injury which might 80 otherwise be occasioned where my movable belt is not employed.

The invention being intended to be defined solely by the claims, is not to be limited to or by details of construction shown or de- 85 scribed.

I claim:

1. In a mechanical organization of the character described; a hearse; a pair of horizontally disposed ways mounted in the 90 interior of the hearse, one way being mounted on each side wall of the hearse; parallelly disposed connected bars supported on and slidably removable from the ways; a pair of spaced rolls rotatably mounted on the 95 bars; and a belt carried on the rolls and adapted to support flowers and the like.

2. In a mechanical organization of the character described; a hearse; a pair of horizontally disposed ways mounted in the 100 interior of the hearse, one way being mounted on each side wall of the hearse; parallelly disposed connected bars supported on and slidably removable from the ways; a pair of spaced rolls rotatably mounted on the 105 bars; a hand-operable wheel on one roll whereby it may be rotated; and a belt carried on the rolls and adapted to support flowers and the like.

3. In a mechanical organization of the 110

character described; a hearse; a frame comprising parallelly disposed connected bars carried inside the hearse and having horizontally disposed members extending in a direction parallel with the bars and adapted to support the belt hereinafter mentioned slidably upon said members; a pair of spaced rolls rotatably mounted on the bars; and a belt carried on the rolls and passing around said members and adapted to support flowers and the like.

4. In a mechanical organization of the character described; a hearse; a pair of horizontally disposed ways mounted in the interior of the hearse, one way being mounted

on each side of the hearse; parallelly disposed connected bars supported on and slidably removable from the ways; a pair of spaced members mounted on the bars; and a belt carried on said members and slidable over them and adapted to support flowers and the like.

In testimony whereof I have hereunto set my hand in presence of two subscribing witnesses, at Grand Rapids, Michigan, this 14th day of November A. D. 1916.

HARRY A. YEIDER.
